United States Patent Office

Des. 184,791
Patented Apr. 7, 1959

184,791

MULTI-PURPOSE CHAIR

Glenn E. Anderson, Seattle, Wash.

Application October 16, 1958, Serial No. 53,011

Term of patent 7 years

(Cl. D15—1)

Fig. 4.

Fig. 5.

Figure 1 is a perspective view of a multi-purpose chair, showing my new design, with the back and tray portions thereof disposed horizontally;

Fig. 2 is a perspective view of said chair, with the back and tray portions thereof disposed uprightly;

Fig. 3 is a view in rear elevation of said chair, with the back thereof disposed horizontally and the tray thereof disposed uprightly;

Fig. 4 is a view in rear elevation of said chair, with the back thereof disposed uprightly and with the tray thereof removed; and

Fig. 5 is a bottom view of said chair, with the back and tray thereof disposed horizontally.

I claim:

The ornamental design for a multi-purpose chair, substantially as shown and described.
